UNITED STATES PATENT OFFICE.

WILLIAM H. KINNEY, OF CHICAGO, ILLINOIS, ASSIGNOR TO KINNEY-ROME COMPANY, OF CHICAGO, ILLINOIS, A CORPORATION.

SPRING STRUCTURE AND METHOD OF ASSEMBLING THE SAME.

Application filed September 2, 1919. Serial No. 321,189.

To all whom it may concern:

Be it known that I, WILLIAM H. KINNEY, a citizen of the United States, and a resident of Chicago, county of Cook, and State 5 of Illinois, have invented certain new and useful Improvements in Spring Structures and Methods of Assembling the Same, of which the following is a specification.

The invention relates to upholstering 10 spring structures such as bed and cushion springs, and more particularly to bed and cushion springs having rows of vertically disposed upholstering springs and horizontally disposed spiral spacing springs. The 15 invention seeks to provide improved means for coupling the upholstering and spacing springs which will securely connect the same, and to provide an improved method of assembling which will facilitate and 20 cheapen the manufacture.

The invention consists in the features of improvement hereinafter set forth, illustrated in its preferred embodiment in the 25 accompanying drawing and more particularly pointed out in the appended claims.

In the drawing, Figure 1 is a partial plan view of the spring structure embodying the present invention. Figure 2 is a detail view 30 on an enlarged scale, parts being shown in vertical section on the line 2—2 of Fig. 1. Figure 3 is an end view of the parts shown in Fig. 2, and Figure 4 is a view similar to one end of Fig. 2 and illustrating a slight modification.

In the manufacture of spring structures 35 of the type to which my improvement more particularly relates, it has heretofore been customary to hold the vertically disposed upholstering springs at proper distances 40 apart by means of small spiral or coil springs having at their ends U-shaped connector loops the crown portions of which encircled the uppermost coils of the upholstering springs, while the members of the 45 loops entered the ends of the spiral spacing springs, each loop being provided with an outwardly projecting hook at its inner end that engaged with the coils of the spacing spring. In such prior structures, the U-shaped connector loops were formed of parallel arms or members and the width of the loop plus the width of the hook at its 50 inner end was so materially greater than the inner diameter of the spacing spring, that in the assembling operation it was nec-

essary to screw the end of the spacing spring over the inner portion of the loop. Inasmuch as there is a connector loop at each end of the spacing spring, in the type of structure above referred to, it was also necessary in the assembling operation to screw the loop first inserted within the spacing spring to a considerable distance beyond that which it would normally occupy, so that by a reverse turning operation of the 60 spacing spring, the opposite end of such spring could be caused to spirally engage or screw on to the connector loop at such opposite end. This method of assembling the parts has been found expensive, and the 65 primary object of my present invention is to enable a material saving of labor, and consequent cost of production, to be effected in the assembling operation.

A designates the upholstering springs that 70 may be of the usual "hour-glass" or like type and B designates the spacing springs that extend between the uppermost coils *a* of the upholstering springs A. In the drawing, I have shown only four of the upholstering springs A but it will be understood, of course, that these springs will be employed in suitable number for a bed or like article in which the spring structure is to be used. Ordinarily, the spacing springs B 75 will be arranged so as to intersect each other, as indicated in Figure 1 of the drawing, but this is a well-known arrangement and forms no part of the present invention. 80 The ends of the spacing springs B are united to the uppermost coils *a* of the upholstering spring A by connector loops C. In the preferred embodiment of the invention, each of these loops is of general U-shape 85 outline; that is to say, the loop comprises arms or members *c* and *c'* that pass within the end portions of the spacing springs B. Preferably, the crown portion of the connector loop C that unites the members *c* and *c'* is arranged with a seat *c*² offset at 90 one side of said crown, the purpose of which seat will presently more fully appear. Each connector loop C has at least one of its ends formed with a hook to engage one of the coils *b* of the spacing spring B. This hook 95 *c*³, as shown more particularly in Fig. 2 of the drawing, is bent outwardly and backwardly from the member *c'* and the end of this hook is preferably turned inwardly to form a guard *c*⁴ that will serve to more 100 105 110

effectively retain the loop after it has been placed in position within the end of the spacing spring B. Preferably, also, the arm or member c of the loop C is made somewhat longer than the arm c' and the end of this arm c is turned inwardly, as at c⁵, to facilitate the insertion of the loop into the end coils of the spacing spring B. In order to more effectively hold the loops C within the ends of the spacing springs B, I prefer to distort or bend inwardly the end portions b' of the outermost coils of the springs B so that after the loops C have been inserted within the ends of the spacing springs B, they cannot work loose therefrom.

The method of assembling the parts hereinbefore described is as follows: The spacing springs B will be extended between the uppermost coils of the upholstering springs A, after which the loops C will be passed around the coils a of the springs A and will be thrust straight through the end coils of the spacing springs B until the outermost coils of such springs bear firmly against the upholstering springs A; and at such time, the uppermost coil of each upholstering spring A will rest within the offset seat c² at the end of the corresponding loop C. The width of the loops C, plus the hooks c³ at their ends, is slightly greater than the inner diameter of the spacing springs B but as these loops C are formed of resilient material, the members or arms will be compressed towards each other so as to permit the straight thrust of the members or arms c and c' of the loops and the hooks c³ into the end coils of the springs B. Inasmuch as the hook c³ of each loop C is preferably formed with a guard c⁴, it will be seen that after the loop has been thrust into the spacing spring B the required distance, the loop may be drawn slightly outward to cause the coil b of the spacing spring B with which it is to engage to pass behind the guard c⁴. By forming the loops C so that they may be thrust straight through the end coils of the spacing springs to the required position for use, the necessity of screwing the spacing springs onto the loops is avoided and hence a material saving in time and labor in the assembling of parts is effected.

The object in forming the loops C with the offset seats c² in their crown portions is to insure the holding of the upper portions of the spacing springs more nearly in line with the coils of the upholstering springs, thus giving a flatter and more uniform surface to the structure; and by thus providing the loops C with offset seats c², the tendency of the loops to turn and twist is also resisted. By so forming the loops C so that they may be thrust straight through the end coils of the spacing springs B, it is

possible to form the end coils of the spacing springs B at the outset with the distorted or inwardly bent portions b', which would not be possible if the loops were so formed, as in prior structures, that the spacing springs had to be united to the loops by screwing the springs onto the loops.

While I have described what I regard as the preferred embodiment of the invention, it is obvious that details of the invention may be varied without departing from the scope thereof. Thus, for example, in Figure 4 of the drawing, I have shown a form of connector loop in which the guard c⁴ is omitted and in which the crown of the loop is provided with an extended portion c⁶ that will enable the loop to be more readily grasped when it is to be inserted in the end of the spacing spring B.

Having thus described my invention, what I claim as new and desire to secure by Letters Patent is:—

1. In a spring structure the combination of upholstering springs, spiral spacing springs extending between the upholstering springs, and connectors adapted to be inserted through the open end and into the body of the spacing spring, each of said connectors comprising a member looped around a portion of the upholstering spring and having a pair of spaced arms, both bent in the same direction in the plane of the loop and inserted into the end of the spacing spring, the bend in one of the arms forming a hook for engaging between two consecutive coils of the spacing spring.

2. In a spring structure the combination of upholstering springs, spiral spacing springs extending between the upholstering springs, and connectors adapted to be inserted through the open end and into the body of the spacing spring, each of said connectors comprising a member looped around a portion of an upholstering spring and having a pair of spaced arms inserted in the end of the spacing spring, one of said arms being formed with an outturned hook for engaging an inner coil of the spacing spring at one side of the latter and the other of which arms resiliently engages the opposite side of the spring to hold the hook engaged with said coil.

3. In a spring structure the combination of upholstering springs, spiral spacing springs extending between the upholstering springs and end connectors on the spacing springs, each of which comprises a member looped around a portion of an upholstering spring and having a pair of spaced arms secured in the end of the spacing spring and hooked onto an inner coil thereof by relative movement of the spacing spring and connector in a plane coincident with the arms of the connector and the axis of the spacing spring.

4. In a spring structure the combination of upholstering springs, spiral spacing springs extending between the upholstering springs and connectors on the ends of the spacing springs engaging the upholstering springs, each of said connectors comprising a loop with a pair of spaced arms inserted straight into the end of the spiral spring and an outturned hook on one of the arms interlocked with an inner coil of the spacing spring by separating tension between the arms.
5. In a spring structure the combination of upholstering springs, spiral spacing springs extending between the upholstering springs and having connectors on the ends engaging the upholstering springs each of said connectors comprising a loop with a pair of spaced arms insertable straight into the end of the spiral spring and an outturned hook on one of the arms yieldingly arranged so as to retract from each successive coil of the spacing spring as the arms of the connector are inserted therein and spring outwardly between two adjoining coils of the spacing spring when the connector is fully inserted and thereby interlock with one of said coils to prevent removal of the connector.
6. In a spring structure the combination of a pair of spaced upholstering springs, a spacing spring interposed between the upholstering springs, a connector at each end of the spacing spring looped around a portion of the adjacent upholstering spring and having a pair of spaced arms inserted straight into the end of the spacing spring, and interlocked with a coil of the spacing spring at a distance from the end, and means on the end of the spacing spring

co-operating with the connector to hold the latter against turning movement as it is inserted in the spacing spring.

7. In a spring structure the combination of a pair of upholstering springs, a spiral spacing spring extending between the upholstering springs, a connector inserted and locked in each end of the spacing spring and engaging a portion of the adjacent upholstering spring and means on each end of the spacing spring engaging the respective connectors for holding said connectors against turning movement as they are inserted in the spacing spring.

8. A spring structure comprising upholstering springs, spiral spacing springs extending between and engaging the ends of said upholstering springs, and connector loops each having upper and lower members inserted and locked in the end of a spacing spring and an off set seat at the bight of each connector loop eccentrically arranged at the outer end of the spacing spring and embracing a portion of the upholstering spring.

9. A spring structure comprising upholstering springs, spiral spacing springs extending between the ends of said upholstering springs, and connector loops engaging said upholstering springs, and having spaced arms inserted in the ends of the spacing springs one of said arms being formed with an outturned hook for engaging a coil of the spacing spring at a distance from the end, said hook being provided with an inturned guard at the end for holding the hook engaged with said coil.

WILLIAM H. KINNEY.
